US00D791486S

(12) **United States Design Patent** (10) Patent No.: **US D791,486 S**
(45) Date of Patent: ** Jul. 11, 2017

(54) **TOOTHBRUSH**

(71) Applicant: **Colgate-Palmolive Company**, New York, NY (US)

(72) Inventors: **Xiang Ji Ding**, YangZhou (CN); **Yu Liu**, Wuxi (CN); **Wen Jin Xi**, Shanghai (CN); **Al Sprosta**, Maplewood, NJ (US); **Kenneth Waguestock**, North Brunswick, NJ (US)

(73) Assignee: **COLGATE-PALMOLIVE COMPANY**, New York, NY (US)

(**) Term: **14 Years**

(21) Appl. No.: **29/497,683**

(22) Filed: **Jul. 28, 2014**

Related U.S. Application Data

(62) Division of application No. 29/390,965, filed on May 2, 2011, now Pat. No. Des. 712,155.

(51) **LOC (10) Cl.** **04-02**

(52) **U.S. Cl.**

USPC **D4/104; D4/138**

(58) **Field of Classification Search**

CLAIM

The ornamental design for a toothbrush, as shown and described.

DESCRIPTION

FIG. 1 is a right front perspective view of a toothbrush in accordance with the new design;

FIG. 2 is a left front perspective view thereof;

FIG. 3 is a left rear perspective view thereof;

FIG. 4 is a right rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

All broken lines shown in the drawings are for environmental purposes only and form no part of the claimed design.
